UNITED STATES PATENT OFFICE.

CHARLES WESLOW, OF NEWARK, NEW JERSEY.

BILLIARD AND OTHER GAME TABLE.

1,259,694.

Specification of Letters Patent. Patented Mar. 19, 1918.

Application filed June 26, 1917. Serial No. 176,937.

To all whom it may concern:

Be it known that I, CHARLES WESLOW, a citizen of the United States, residing in Newark, in the county of Essex and State 5 of New Jersey, have invented certain new and useful Improvements in Billiard and other Game Tables, of which the following is a specification.

The object of my invention is to provide 10 an improved pool or billiard table for use in playing any or all of the various games of billiard or pool type, which are played upon a substantially horizontal table surrounded by cushioned rails having resilient 15 inner surfaces, the impact against which throws the ball away therefrom; and such tables of my improved form, are of an extremely simple and cheap form of construction; easily and quickly adjusted into level; 20 and the resilient or cushioned portions of the rails of the table, are easily and quickly renewable at very small cost.

In Figures 1 to 3 inclusive I have shown 25 my said invention as adapted to a table of the pool-type having six pockets, one at each corner, and one upon either of the longest dimensioned sides, located at or adjacent to the centers thereof.

My said invention is fully shown and described in the following specification, of 30 which the accompanying drawing forms a part; wherein similar letters or numerals of reference designate like or equivalent parts wherever found throughout the several 35 views, and in which:

Fig. 1 shows a top side view in perspective of my improved form of six-pocket pool-table; while Figs. 2 and 3 are views in detail of various portions of the table so 40 constructed; and

Fig. 4 is a top side view in perspective of the corner portion of a table, showing my invention as adapted for and applied to tables of the well-known billiard table type, 45 unprovided with pockets.

Fig. 5 is a detail side view in vertical section of a corner of the table and its supporting leg of a modified form of construction.

Fig. 6 is an end inner view in detail of a 50 modified form of cushioning rail.

Fig. 7 is a top plan view of a table corner of the pool-table shown in Figs. 1 and 2 showing such table transformed into a non-pocket billiard-table, by the insertion in the 55 pockets of removable pocket-closing blocks.

Fig. 8 is a perspective view of another form of table.

Fig. 9 is a perspective view of a detail thereof. 60

Fig. 10 is a fragmental sectional view showing another form of adjustable leg.

Referring to the drawing:

The reference letter A designates the bed or top portion of the table, usually of wood 65 or casting composition provided with a smooth upper surface, which may be of any suitable material; and B are the side rails superposed upon and rigidly secured to such top or bed A at the ends and sides thereof, 70 in any suitable manner, usually by screws or nails as shown. In the pool-table type, pockets C are made in and through the table-top or bed at the corners, and like pockets C', adjacent to the center of each of 75 the longest sides, and the ends of the side and end rails B are angled as indicated at 1, so as to permit free passage of the balls into such pockets C and C', through which they pass into a suitable box or receptacle K. 80

The side rails D are provided at the ends with substantially V or U shaped slots 3, usually and preferably formed only in the straight faced end portions 4 of such rails; and to form the resilient, elastic rail-cushions to throw back the balls upon the table-top A, along the inner side of such rails are arranged suitable resilient or elastic strips or bands D, usually and preferably of highly elastic rubber, which are preferably 90 tightly stretched, and held in place by having the ends thereof drawn tightly into the V or U shaped slots 3 in the rail ends, as indicated at 5 of Fig. 1; or the same may be secured in place and preferably under tension in any other desired manner. 95

Such bands may be of any suitable resilient material, that will cause the balls to rebound therefrom with what may be termed a billiard deflect; and in Fig. 6 instead of 100 the resilient elastic rubber-band shown in Fig. 1, I have shown a metallic coil-spring used in the place of such rubber band. For cheapness of construction, and in order to be able to quickly transform the pocket pool-table as shown in Fig. 1, into a non-pocketed billiard table, upon which an ordinary 3 or 4 ball, or a pin-pool billiard game may be executed; and in Fig. 7 I have shown in detail a top plan view of a removable plug 110 in position therein, which may be inserted in the corner pockets of the table to close

the same, and transform such pocket pool-table into a regular non-pocketed billiard-table. As shown in detail in Fig. 7, the pocket is closed by a plug indicated by O, which is usually of the form shown, and like the side-rails made of wood, which plug closes such corner-pocket; and stretched across the reentrant right-angled front of such pocket-plug O, by having the ends thereof tightly stretched or drawn into the V or U shaped slots of such plug are the ends of the resilient bands D', similar to the bands D of the main portion of the main-rails; but as this resilient band must be brought into the corner into the form of a right angled reentrant triangle the center of such band D' is secured in place by a nail or bolt 10; and for the purpose of securing the plug 11 in position in the pocket a removable securing pin is inserted in the corner-plug when in position in the angle of the wire stop-guard E.

Each of the pockets C and C' is provided above the same with a suitable stop-guard E to deflect the balls into the pockets and prevent the same from passing off the table; each usually and preferably consisting of a wire bent into the outwardly bowed form shown in Fig. 1, and each having downwardly extending prongs bent at right angles thereto at either end, which fit into suitable perforations at 6, formed to receive them in the upper portions of the side rails B. The plugs which fill the center pocket C' differ only from the plugs which fill the corner pockets in that the rubber bands D' have no angles, and are straight as indicated in dotted lines in Fig. 1.

It will be seen that when the rubber or other material used for the cushions D or D' becomes deteriorated through age or use, that the old worn-out bands may be instantaneously removed, and new and perfect ones as instantaneously replaced in position.

As hereinbefore described, the game table consists only of a legless bed A, and the other described parts superposed thereupon and the same may be placed upon any table or other suitable support, and used for playing. However, I may provide feet F which when not desired for use, may be taken off and stored away, and will take up but little space; and when such supporting feet are used, the same may be of any desired form and material, usually wood; and as shown in Fig. 5, where the feet are desired to be removably and adjustably attached to the bed A, they may be secured thereto by suitable screws 12 and provided with rounded tips 13' of rubber or metal or other suitable material. Another form in which the feet F are removable and readily adjustable as to height for leveling the table is shown in Fig. 2, wherein the main body portion of the foot consists of a main foot-

member 13 provided with a like tip 13'. In the top of the foot-member 13 is located a substantially U-shaped resilient bow or leg-holder, consisting of a securing spring-member, fitting into the cavity 14' formed in or adjacent to a corner of the bed. By these arrangements the table bed can be leveled, irrespective of the irregularity of the floor or other surface upon which it is supported.

In the modified form of Figs. 8 and 9, the side rails B' are provided with inner grooves in which lie the cushions, which in this case comprise a single endless band D''' of rubber or the like. In Fig. 8, some of the pockets are shown exposed, as for a pool-table, while others are closed, as for a billiard table.

When the table is used as a pool-table and the pockets exposed, the band at each corner pocket is carried behind a block M placed between the ends of the adjacent rails B' to the outside of the pockets. At the side pockets, the band is carried around the uprights N secured to the side of the bed at the outside of the side pockets. The band D''' is made short enough to give sufficient tension so that by means of this arrangement, the cushions forming portions of the band are firmly held in the grooves.

When the table is to be used as a billiard table, the band is removed from around the uprights N, and the space between the ends of the side rails D''' is filled with a grooved plug O made to fit snugly in said space and form a continuation of the front face of the side rails, the groove P of the plug forming a continuation of the groove of the side rails.

At the corner the pocket is closed by a notched plug Q, the notch forming the corner of the table. This notch is also provided with grooves R forming a continuation of the grooves of the side rails, and terminating at the cut-away portion S at the tip of the plug. The elastic band is passed through said grooves and said cut-away portion and around the block M as shown. The notched plug is held in place by the engagement of its beveled portion T under the under-cut portion U of the corner block M.

In the form of foot F' shown in Fig. 10, the foot member 13'' is provided with an axial cavity 15 passing entirely therethrough, in which is placed a resilient split key 16 having its lower curved end 16' extending below the foot member to form a bearing surface, and its upper resilient end portions extending into and frictionally engaging in the cavity 14' in the bed of the table. The height of these feet may be adjusted by drawing the resilient end portions part of the way out of said cavity, or the legs may be removed by drawing the resilient members all of the way out.

Many modifications in the construction of

my improved form of billiard and pool-table herein shown, described and claimed, may be made without departing from the scope of my invention and I do not intend to limit myself to the exact forms thereof shown.

5 I claim:—

1. In a device of the class described, a table-top or bed; a railing superposed upon such table or bed forming a raised boundary; and a resilient or elastic cushioning strip band superposed longitudinally upon the inner face of such railing secured in position by having the ends thereof secured in slots in the rail members under tension.
- 10 2. In a device of the class described, a table-top or bed, a railing superposed upon such table or bed forming a rectangular raised boundary, composed of four rail-members and a resilient or elastic cushioning strip band, superposed upon the inner face of such railing and secured in position by having the ends thereof secured in binding securing slots in the ends of the rail members.
- 15 3. In a device of the class described, a

table-top or bed having pockets formed 25 therein at the corners and at the centers of the longest sides; side and end rails mounted upon and secured to said table top or bed, extending from pocket to pocket, having the ends cut off at the inner side portions at an 30 angle of approximately 45 degrees, and at a substantially right angle at the rear portions; binding securing-slots in the right angled portions of such rails, the space between the ends of such rails being sufficient 35 to permit of the balls dropping into the pockets; a cushioning strip band of resilient material secured at the ends in the binding securing-slots of each of the rails; and stops extending over the pockets from the end of 40 one rail to the abutting end of another, for deflecting the balls into the pockets and for preventing the same from passing out over such pockets.

CHARLES WESLOW.
